CORING APPARATUS

Wilbur J. Crites, Bartlesville, Okla., assignor to
Phillips Petroleum Company, a corporation of
Delaware

Application March 24, 1941, Serial No. 385,016

10 Claims.

(Cl. 255—72)

This invention relates to coring and more particularly to apparatus for obtaining representative cores from subsurface formations.

It is common practice in the petroleum industry to obtain cores from hydrocarbon-bearing formations for the purpose of determining certain reservoir characteristics which are useful in predicting reservoir fluid performance. Virgin reservoirs may be cored usually with a relatively high percentage of core recovery. Depleted formations at shallow depths may be cored with equal success. On the other hand, coring depleted reservoirs at greater depths yields a relatively low percentage of core recovery. In the present practice of coring, a drilling fluid is usually circulated downwardly through the drill pipe and thence upwardly through the annular space between the bore hole and the drill pipe to the surface of the ground where entrained formation cuttings are removed from the drilling fluid. As greater depths of formation are drilled or cored, the pressure of the drilling fluid column increases proportionately. In coring depleted hydrocarbon reservoirs, the pressure of the column of drilling fluid may become so great that the fluid and entrained formation cuttings will flow into the porous formation where the solid materials and the fluid will plug off the pore spaces of the formation instead of circulating to the surface of the ground. If an unconsolidated formation is cored, drilling fluid under considerable pressure will wash away certain portions of the core so that that which remains is non-representative of the formation cored. If a consolidated formation is cored, the drilling fluid will penetrate the core, contaminating the formation fluid therein. Non-representative or contaminated cores have little or no value for analytical interpretation.

By the practice of my invention I am able to obtain representative formation cores, which are not contaminated by drilling fluid. The invention is especially useful in coring low pressure and non-consolidated formations, as the pressure of the drilling fluid on the face of the formation is approximately that of the formation. When a constant load is carried on the core bit, the rotational speed of the bit is inversely proportional and the developed torque is directly proportional to the hardness of the formation being cored.

It is the primary object of my invention to obtain representative cores from subsurface formations.

Another object of my invention is the provi-

sion of apparatus for obtaining representative cores from low pressure and non-consolidated formations.

A further object of my invention is the provision of apparatus for obtaining subsurface formation cores which are not contaminated with drilling fluid.

These and additional objects and advantages will be apparent to persons skilled in the art by reference to the following description and annexed drawings, wherein—

Figure 1 is an elevation view of one embodiment of my invention, partly in cross section;

Figure 2 is an elevation view of a second embodiment of my invention, partly in cross section;

Figure 3 is an enlarged horizontal cross section view of the driving mechanism, taken along the line 3—3 of Figure 1, and;

Figure 4 is a sectional view of the driving mechanism, taken along the line 4—4 of Figure 3.

Referring to Figure 1, I have shown a casing 10 which extends downwardly in a bore hole 11 from the surface of the ground (not shown). A drill stem 12 is suspended and rotated within casing 10 in a well known manner from the surface of the ground. It will be noted from the drawing that the lower portion of the drill stem comprises a coring assembly 13 which consists essentially of a receiving chamber 14, a drilling fluid supply chamber 15, a differential drive mechanism 16, an annular space 17, an inner core barrel 18, and a core bit 19. The upper part of bit 19 is grooved to receive the lower portion of drill stem 12 in such a manner that the drill stem is free to rotate irrespective of the rotation of the bit. A fluid, such as an oil, which is used in operating my device, cools and lubricates the bit and carries away the formation cuttings made thereby.

Chamber 14 is formed by a cylindrical wall 20, which is a portion of the drill stem, intermediate a plug 21 and a filtering element 22 which are positioned within the drill stem and provide the top and bottom, respectively, of the chamber. The upper part of wall 20 has openings 23 which allow the chamber to communicate with an annular space 24 that is formed by the cased and uncased parts of the bore hole and the drill stem. Supply chamber 15 is also formed in the drill stem and is positioned intermediate filter 22 and driving mechanism 16.

Turning next to Figures 3 and 4 for a description of the driving mechanism, I have shown a common type of positive displacement

rotary pump 25 which serves as a fluid transmission or driving means. Any type of positive displacement rotary pump may be employed in the practice of my invention. It is to be noted that the rotary pump 25 is positioned in and secured to drill pipe 12 by means of an outer housing 26. An inner partition 27, which allows communication between the rotary pump and supply chamber 15 through an inlet 28 and with annular space 17 through a restricted outlet 29, of smaller diameter than inlet 28, contains an idler gear 30 which rotates on a fixed idler pin 31 and meshes with a rotor 32. The rotor, which is secured to a shaft 33, also rotates within the inner partition, and cooperates with the idler to pump fluid from inlet 28 through outlet 29. A fixed crescent-shaped member 34 is positioned between the rotor and the idler. Fluid from within the pump is prevented from leaking out around shaft 33 by a packing gland 35 which is placed in the lower portion of housing 26.

Referring again to Figure 1, it will be noted that shaft 33 is secured to inner core barrel 18. The inner core barrel is threadedly attached to bit 19 and contains a check valve 36, which is positioned near the upper end of the core barrel, and one or more perforations 37, which are provided between the valve and the upper end of the core barrel. This arrangement of the valve and perforations provides a means for discharging fluid from the core barrel to space 17 in order to prevent the pressure of the fluid in the core barrel from exceeding the pressure of the fluid in annular space 17. The accumulation of fluid in the core barrel occurs during the coring operation and if allowed to remain in the core barrel at pressures greater than the pressure in space 17 may cause injury to a core, which is received in the core barrel. The lower part of the core barrel is provided with a retaining means or core catcher 38 which allows the core, which is cut from a formation by the bit, to enter core barrel 18 through a passage 39 therein during the coring operation. When the coring assembly is being removed from the well bore, the retaining means holds the core in the core barrel. In addition to a central core passage 39, bit 19 is provided with a plurality of fluid passages 40 which allow fluid from annular space 17 to lubricate and cool the bit and to carry away formation cuttings which are chipped from the formation during the coring operation by a plurality of cutters 41. It is to be noted that the bit contains a packing element 42 at the base of drill stem 12, which prevents leakage of the fluid around the base of the drill stem.

In the operation of this embodiment of my invention, the assembly shown in Figure 1 is lowered into bore hole 11 in the usual manner from the surface of the ground. A predetermined amount of circulating oil is injected into annular space 24 until the hydrostatic head of the oil is substantially equal to the formation pressure. In reservoirs where my invention may be practiced, the formation pressure is generally sufficient to allow the oil to fill chambers 14 and 15, annular space 17, and annular space 24 to a point above openings 23 in the receiving chamber. The normal circulation of the oil through the apparatus may be thought of as starting in supply chamber 15 from which it enters inlet 28 of pump 25 and is pumped through outlet 29 into annular space 17. The oil leaves the annular space flowing through passages 40 in bit 19 to lubricate and cool the bit. The oil entrains cuttings made by

the bit and travels upwardly in annular space 24 entering receiving chamber 14 through openings 23. Filtering element 22 separates the circulating oil from the cuttings, retaining the cuttings above the filter and allowing the oil to pass downwardly into supply chamber 15 from which it may be recirculated.

It will be noted the circulation is maintained by pump 25. Further, the rate of circulation is directly proportional to the weight placed on the bit and the hardness of the formation. The rotational speed of drill pipe 12 may be maintained at a constant rate irrespective of the rotational speed of bit 19. If the bit is in a stationary position and the drill stem is rotated at a constant speed, a certain volume of oil will be pumped and a torque will be developed in the pump which is sufficient to overcome the load on the bit and cause it to turn in the same direction as the drill pipe, but at a slower speed. As long as the weight on the bit remains constant, the differential speed between the bit and the drill pipe and a constant rate of circulation will be maintained. Further, unless there is a resistance to turning of bit 19, it will rotate at substantially the same speed as drill pipe 12, however, under this condition, no fluid will be transmitted through pump 25. This is the case when the drill pipe is held off the bottom of bore hole 11. On the other hand, if bit 19 is prevented from turning while drill pipe 12 rotates at a constant speed, a maximum torque is developed and a maximum rate of circulation is obtained. This is analogous to setting full weight on the bit while coring an extremely hard formation and thus preventing rotation of the bit. The available torque for rotating the bit actually is the torque developed in pumping oil through pump 25, as bit 19 is directly connected to the pump rotor by core barrel 18 and shaft 33. A torque is developed in pumping oil, as the pump receives fluid through inlet 28 and discharges it through restricted outlet 29. All parts of the pump are responsive to the rotation of the drill pipe except rotor 32, which is responsive to the torque developed in pumping oil through the pump. If there is a differential speed of rotation between bit 19 and drill pipe 12, oil will be pumped. In the practice of my invention, the rotational speed of bit 19 and the volume of oil circulated by the pump are functions of the weight which is placed upon the bit. Furthermore, the speed of the bit varies inversely as the hardness of the formation, whereas the volume of oil circulated varies directly as the hardness of the formation. In coring a soft formation, bit 19 will rotate more rapidly than it will in coring a hard formation, while the rate of fluid circulation in coring a soft formation will be less than in coring a hard formation. This feature of my invention eliminates washing away the soft portions of a formation core by high velocity fluid.

In describing a second embodiment of my invention, I have designated like parts by the same reference numerals. By referring to Figure 2, it will be noted that in this embodiment bit 19 is bored to receive and support core barrel 18 and is threadedly attached to an outer member 43 which bears at the top against drill pipe 12. The top of the outer member is provided with a spider 44 by which the member is secured to shaft 33. A plurality of spacing members 45 are positioned in annular space 17 to align core barrel 18, which may remain stationary or rotate independently of bit 19. In addition to core re-

taining means 38, a second pair of core catchers 46 may be provided in core barrel 18 to aid in retrieving the core. The top of the core barrel has a conduit 47 which establishes communication between the top of the core barrel and annular space 24 and through which the pressures within the core barrel and the annular space are equalized. It will be noted that a packing gland 48 is placed around conduit 47 in the top of the core barrel. The packing permits rotation of the core barrel and prevents the circulating oil from entering the core barrel from space 17.

The operation of this second embodiment is very similar to the operation of the first. The torque developed in pump 25 turns outer member 43 and bit 19. The fluid circulation is identical to the first embodiment. Similarly, the rotational speed of the bit and the volume of oil circulated are functions of the weight placed on the bit.

It is to be understood that the forms of my invention, herewith shown and described, are to be taken as preferred examples of the same, and that various changes in shape, size and arrangement of parts may be resorted to without departing from the spirit of my invention, or the scope of the subjoined claims.

I claim;

1. In coring apparatus, the combination comprising a conduit adapted to be rotated in a well bore; a pump including a casing secured to and rotatable with the conduit and a rotor in the casing; core cutting and retaining means connected to the rotor and adapted to engage the bottom of the well bore; and liquid supplied to the pump, whereby, upon rotation of the conduit and the pump casing, the said means will be rotated against the resistance of its contact with the bottom of the well bore.

2. In coring apparatus, the combination comprising a drill stem adapted to be rotated in a bore hole; a pump including a casing secured to the drill stem and rotatable therewith, an inlet, an outlet, and a rotor in the casing; a coring tool connected to the rotor and adapted to engage the bottom of the bore hole; a passage in the coring tool communicating with the pump outlet; and liquid supplied to the pump through the inlet thereof, whereby, upon rotation of the drill stem and the pump casing, the coring tool will be rotated against the resistance of its contact with the bottom of the bore hole.

3. In coring apparatus, the combination comprising a drill stem adapted to be rotated in a bore hole; a pump including a casing secured to the drill stem and rotatable therewith, an inlet, an outlet, and a rotor in the casing; a coring tool connected to the rotor and adapted to engage the bottom of the bore hole; said coring tool including rotary core cutting means, core receiving means, and a passage communicating with the pump outlet; and liquid supplied to the pump through the inlet thereof, whereby, upon rotation of the drill stem and the pump casing, the coring tool will be rotated against the resistance of its contact with the bottom of the bore hole.

4. In coring apparatus, the combination comprising a drill stem adapted to be rotated in a bore hole; a pump including a casing secured to the drill stem and rotatable therewith, an inlet, an outlet, and a rotor in the casing; core drill means connected to the rotor and adapted to engage the bottom of the bore hole; a core pas-

sage in said means; a fluid passage in said means communicating with the pump outlet; a receptacle communicating with the core passage for receiving and retaining core material, and liquid supplied to the pump through the inlet thereof, whereby upon rotation of the drill stem and the pump casing, the core drill means will be rotated against the resistance of its contact with the bottom of the bore hole.

10 5. In coring apparatus, the combination comprising a drill stem adapted to be rotated in a bore hole; a positive displacement rotary pump including a casing within the drill stem and secured thereto so as to rotate therewith, said
15 casing forming a partition across the interior of the drill stem, an inlet establishing communication between the casing and the portion of the drill stem above the casing, an outlet establishing communication between the casing and the
20 portion of the drill stem below the casing, and a rotor in the casing; a coring tool rotatably coupled to the lower end of the drill stem and connected to the pump rotor so as to rotate therewith, said coring tool being adapted to engage the
25 bottom of the bore hole; and liquid supplied to the pump casing through the inlet thereof, whereby, upon rotation of the drill stem and the pump casing, the coring tool will be rotated against the resistance of its contact with the
30 bottom of the bore hole.

30 bottom of the bore hole.

6. In coring apparatus, the combination comprising a conduit adapted to be rotated in a bore hole, a positive displacement rotary pump including a casing secured to the conduit and rotatable therewith, said casing forming a partition across the interior of the conduit, an inlet communicating with the casing and the portion of the conduit thereabove, an outlet communicating with the casing and the portion of the conduit therebelow, and a rotor in the casing, a coring tool rotatably coupled to the lower end of the conduit and including a core drill connected to the pump rotor so as to rotate therewith and adapted to engage the bottom of the bore hole, a fluid passage extending through the core drill and communicating with the pump outlet, a core receiving receptacle, and a core passage in the core drill communicating with said receptacle; and liquid supplied to the pump casing through the inlet thereof, whereby, upon rotation of the conduit and the pump casing, the core drill will be rotated against the resistance of its contact with the bottom of the bore hole.

7. In coring apparatus, the combination comprising a conduit adapted to be rotated in a bore hole, a positive displacement rotary pump including a casing secured to the conduit and rotatable therewith, said casing forming a partition across the interior of the conduit, an inlet 55 communicating with the casing and the portion of the conduit thereabove, an outlet communicating with the casing and the portion of the conduit therebelow, and a rotor in the casing, a coring tool rotatably coupled to the lower end of the conduit and including a core drill connected to the pump rotor so as to rotate therewith and adapted to engage the bottom of the bore hole, a fluid passage extending through the core drill, a core receiving receptacle disposed within the 60 conduit and spaced therefrom to form an annular passage therewith communicating with the pump outlet and the fluid passage and positioned intermediate the pump casing and the core drill, and a core passage in the core drill communicating 65 with said receptacle; and liquid supplied to the 70 conduit.

pump casing through the inlet thereof, whereby, upon rotation of the conduit and the pump casing, the core drill will be rotated against the resistance of its contact with the bottom of the bore hole.

8. In coring apparatus, the combination comprising a first conduit adapted to be rotated in a well bore; a second conduit extending below the first conduit and rotatable with respect thereto, said conduits being in communication; a pump including a casing forming a partition across the first conduit and secured thereto so as to rotate therewith, an inlet establishing communication between the casing and the portion of the first conduit thereabove, an outlet establishing communication between the casing and the second conduit, and a rotor in the casing fixedly connected to the second conduit; a coring tool connected to the second conduit and adapted to engage the bottom of the bore hole; and liquid supplied to the pump casing through the inlet, whereby, upon rotation of the first conduit and the pump casing, the second conduit and the coring tool will be rotated against the resistance of its contact with the bottom of the well bore.

9. In coring apparatus, the combination comprising a first conduit adapted to be rotated in a well bore; a second conduit extending below the first conduit and rotatable with respect thereto, said conduits being in communication; a pump including a casing forming a partition across the first conduit and secured thereto so as to rotate therewith, an inlet establishing communication between the casing and the portion of the first conduit thereabove, an outlet establishing communication between the casing and the second conduit, and a rotor in the casing fixedly connected to the second conduit; a coring tool including a core drill connected to the second conduit and adapted to engage the bottom of the bore

hole, a fluid passage extending through the core drill and communicating with the pump outlet, a core receiving receptacle, and a core passage in the core drill communicating with said receptacle; and liquid supplied to the pump casing through the inlet thereof, whereby, upon rotation of the first conduit and the pump casing, the second conduit and the core drill will be rotated against the resistance of its contact with the bottom of the well bore.

10. In coring apparatus, the combination comprising a first conduit adapted to be rotated in a well bore; a second conduit extending below the first conduit and rotatable with respect thereto, 15 said conduits being in communication; a pump including a casing forming a partition across the first conduit and secured thereto so as to rotate therewith, an inlet establishing communication between the casing and the portion of the first 20 conduit thereabove, an outlet establishing communication between the casing and the second conduit, and a rotor in the casing fixedly connected to the second conduit; a coring tool including a core drill connected to the second conduit 25 and adapted to engage the bottom of the bore hole, a fluid passage extending through the core drill, a core receiving receptacle within the second conduit and spaced therefrom to form an annular passage therewith communicating with 30 the pump outlet and the fluid passage and positioned intermediate the pump casing and the core drill, and a core passage in the core drill communicating with said receptacle; and liquid supplied to the pump casing through the inlet thereof, 35 whereby, upon rotation of the first conduit and the pump casing, the second conduit and the core drill will be rotated against the resistance of its contact with the bottom of the well bore.

WILBUR J. CRITES.
